5 Claims. (Cl. 60—18)

This invention relates to a hydraulic starting and pumping system.

The use of hydraulic motors for starting internal combustion vehicle-propulsion engines is known in the prior art. Such hydraulic motors are generally driven by pressure fluid supplied by motor-driven auxiliary pumps and the known systems have proven to be complex, heavy, space-consuming and expensive.

In the copending application of Edward V. Manning and John P. Mentink, Serial No. 92,052, filed February 27, 1961, and entitled "Hydraulic System," a hydraulic starting system is disclosed in which a variable displacement hydraulic motor-pump unit is driven as a motor by fluid supplied from a pressure fluid source, such as a pressure accumulator, having a decaying pressure characteristic. Automatic control means are provided for controlling the displacement of the hydraulic unit in a predetermined manner in accordance with the decaying characteristic of the source. By the use of such a pressure fluid source, the starting system is capable of being completely self-contained in the vehicle. After the internal combustion engine has been started, the hydraulic unit is designed to be driven as a pump by the internal combustion engine to recharge the accumulator and to supply fluid to the hydraulic system of the vehicle. By causing the hydraulic motor of the starting system to operate also as a pump subsequent to starting of the internal combustion engine, the need for auxiliary pumping apparatus is eliminated and the weight of the vehicle is reduced.

The object of the present invention is to provide an improved starting and pumping system of the type disclosed in the Manning and Mentink application referred to above. The invention is characterized by the provision of means operable—during motoring—to position the displacement control element of the variable displacement unit in a maximum stroke-establishing motoring position as long as the pressure of the source is above a predetermined value and to position the control element in a zero stroke-establishing neutral position when the pressure is below this value, and operable—during pumping—to position the control element in a maximum stroke-establishing pumping position when the pumping pressure of the unit is below a predetermined operating value and to move the control element gradually toward its neutral position as the pumping pressure rises from this operating value to the desired maximum.

The hydraulic motor-pump unit of the starting and pumping system is of the "overcenter" type employing a rotary group of elements consisting of a cylinder barrel having longitudinal bores therein and reciprocating pistons mounted in said bores, said rotary group being mounted for rotation with respect to an angularly adjustable cam plate suspended in the engine housing. As the rotary group of elements rotates relatively to the cam plate, reciprocating motion is imparted to the pistons. The stroke of the pistons and the displacement of the hydraulic unit are dependent upon the angle of inclination of the cam plate. The cam plate is movable between maximum stroke-establishing motoring and pumping positions on opposite sides of a zero stroke-establishing neutral position. Such a hydraulic unit presents the advantage that only one high pressure line is required since the high pressure inlet port of the hydraulic unit during motoring becomes the high pressure discharge port during pumping.

2

According to the preferred embodiment of the invention, a shiftable spring assembly is provided for continuously biasing the displacement control member toward its maximum stroke-establishing pumping position during the 5 motoring and pumping operations of the hydraulic unit. A shifting motor is provided for placing the spring assembly, during motoring, in a first position in which a given biasing force is applied to the control member, and for placing the spring assembly, during pumping operation, in a second position in which a greater biasing force is applied to the control member. Pressure-responsive means are provided for placing the control member in its maximum stroke-establishing motoring position (against the counteracting bias of the spring assembly) when the 10 pressure of the source is above a predetermined value. During pumping operation, the pressure-responsive means operate to position the control member in its neutral position (against the counteracting bias of the spring assembly) when the pumping pressure equals a predetermined value. According to another feature of the 15 invention, the spring assembly is designed to constitute a stop which operates, during pumping operation of the hydraulic unit, to prevent movement of the control element from its neutral position toward its maximum stroke-establishing motoring position.

Other objects and advantages of the invention will become more apparent from a study of the following specification when considered in conjunction with the accompanying drawings, in which:

30 FIG. 1 is a sectional view of the hydraulic unit of the starting system, the displacement control member being shown in its maximum stroke-establishing motoring position.

35 FIG. 2 is a schematic diagram of the hydraulic starting system, the displacement control element of the hydraulic unit being shown in its zero stroke-establishing neutral position.

40 The hydraulic starting system includes a variable displacement hydraulic motor-pump unit 3 of the "overcenter" type disclosed in detail in the copending application of Tadeusz Budzich and Edward V. Manning, Serial No. 789,996, filed January 29, 1959, now abandoned, and entitled "Overcenter Hydraulic Starter Pump." The hydraulic unit comprises a housing 4 having a drive shaft 5 journaled therein to which is connected the rotary cylinder barrel 6. The rotary cylinder barrel 6 is in contiguous engagement at one end with the adjacent end face of stationary valve plate 7, which face contains arcuate high and low pressure ports in communication, respectively (through internal housing passages, not shown), with the 45 housing high and low pressure ports 8 and 9 illustrated in FIG. 2. The cylinder barrel 6 contains a circumferential series of through longitudinal cylinder bores 11 which are arranged to register sequentially with the arcuate ports in valve plate 7 as the cylinder barrel rotates. Pistons 50 12, formed with spherical heads 13 for connection with supporting shoes 14, are mounted in the cylinder bores for reciprocation by cam plate 15 and return plate 16.

55 The cam plate 15 is supported in housing 4 by cam plate yoke portions 15a and fixed housing-secured trunnions 17 (see FIG. 2) for angular movement about a horizontal pivot axis extending in a direction normal to and intersecting the axis of drive shaft 5. The angular 60 position of cam plate 15 determines the length of the strokes of pistons 12, and the cam plate is free to move between maximum stroke-establishing motoring (FIG. 1) and pumping positions on opposite sides of a zero stroke-establishing neutral (FIG. 2) position. Shiftable spring 65 assembly 18 is provided for biasing cam plate 15 in the clockwise direction about its pivot axis. This spring assembly comprises a first spring seat sleeve 19 connected at one end with the cam plate 15 by connecting rod 21,

a second spring seat sleeve 22 arranged for sliding movement at one end within an axial bore in the other end of sleeve 19, and a coaxial preloaded coil spring 23 seated on the peripheral flange portions 19a and 22a of sleeves 19 and 22, respectively. When sleeve 22 is in its FIG. 1 position in engagement with the housing inner wall surface 4a, spring 23 reacts with a first biasing force between sleeve portions 19a and 22a to displace sleeve 19 to the left and thereby place cam plate 15 in its maximum stroke-establishing pumping position as shown by the broken lines in FIG. 2.

Motor means 24 are provided for shifting sleeve 22 to the left to a second position in which spring 23, during pumping operation of the hydraulic unit, biases cam plate 15 toward its maximum stroke-establishing pumping position with a greater biasing force. This motor 24 includes a cylinder 25 provided with an axial tubular extension 25a secured within an opening in the housing 4. Reciprocable piston 26 is mounted in cylinder 25 and is provided with a piston rod 27 movable within extension 25a. The second sleeve 22, which is mounted for sliding movement on this stationary extension 25a, has an end wall 22b against which the free end of piston rod 27 abuts. When pressure fluid is introduced into working chamber 24a of motor 24 to displace piston 26 to the left into engagement with the left-hand end wall of cylinder 25, piston rod 27 shifts sleeve 22 to the left and thereby increases the spring biasing force on cam plate 15. It is important to note that when sleeve 22 is in this left-hand position, it serves as a cam stop preventing cam plate 15 from moving from its neutral position toward its FIG. 1 position.

Cam plate 15 is movable in the counterclockwise direction against the counteracting biasing force of spring assembly 18 by a hydraulic positioning motor 31 including a cylinder 32 secured to housing 4 and a reciprocable piston 33 that is connected with cam plate 15 by connecting rod 34. Piston 33 is moved to the left in its cylinder by the application of pressure fluid to working chamber 31a.

The drive shaft 5 extends through an opening in the housing 4 and terminates in a splined coupling 36 to which the internal combustion engine 37 is connected via conventional mechanical coupling 38.

Referring now to FIG. 2, an accumulator 40, which constitutes a pressure fluid source having a decaying pressure characteristic, is connected with the housing high pressure port 8 via conduit 41 containing three-way inlet valve 42. Valve 42 is operable between a first position in which it connects conduit portion 41a with conduit portion 41b and a second position in which it connects conduit portion 41b with the vehicle hydraulic system conduit 43. Housing low pressure port 9 is connected with sump 44 via conduit 45.

The state of energization of positioning motor 31 is controlled by the dual-pressure control valve 46. This control valve includes a housing having an inlet passage 47 connected with high pressure port 8 via conduit 48, a motor passage 49 connected with positioning motor working chamber 31a via conduit 51, and an exhaust passage 52 connected with sump 44 via conduit 53. The control valve housing includes a longitudinal bore 54 in one end of which is mounted the reciprocable valve plunger 55 having lands 56, 57 and 58 separated by grooves 59 and 61, respectively, for controlling the communication between the various valve housing passages. Through longitudinal slots 62 are provided in the outer periphery of land 58.

Mounted for reciprocation in the other end of the valve housing bore is the spring seat 63. Preloaded spring 64, reacting between spring seat 63 and plunger 55, urges the seat to the left to its FIG. 2 position in which it abuts housing wall projection 65, and urges the plunger 55 in the opposite direction into engagement with the other bore end wall to effect venting of the working chamber 31a of positioning motor 31 via conduit 51, passage 49, 70

groove 59, passage 52 and conduit 53. Spring chamber 66 is in continuous communication with sump conduit 53 via conduit 67.

When seat 63 is in its FIG. 2 position, spring 64 establishes a first "reference pressure" condition of operation of control valve 46 as will be described in greater detail below. Spring seat 63 constitutes the piston of hydraulic piston motor means and, when pressure fluid is introduced into working chamber 63a to shift the seat to the right to a second position in which it engages fixed stop 69, the preloading of spring 64 is increased to establish a second "reference pressure" condition of operation of control valve 46.

The spring assembly shifting motor 24 and the motor for shifting spring seat 63 are operated simultaneously by auxiliary valve 71. This auxiliary valve includes a housing having an inlet port 72 connected with high pressure port 8 via conduit 73 and conduit portion 48a, a motor port 74 connected with working chamber 24a via conduits 75a and 75b and with working chamber 63a via conduits 75a and 75c, and a pair of exhaust ports 76 and 77 connected with sump 44 via conduits 78 and 79, respectively. The valve housing contains a longitudinal bore in which is mounted the movable valve plunger 81 having lands 82, 83 and 84 separated by grooves 85 and 86. Spring 87, mounted in the left-hand end of the bore, biases plunger 81 to the right to a first or energizing position in which working chambers 24a and 63a communicate with high pressure port 8 via branch portions 75b and 75c, respectively, common portion 75a, port 74, groove 85, port 72, conduit 73 and conduit portion 48a. Plunger 81 carries an axial projection 31a on which is secured the armature 88 of stationary solenoid coil 89. When solenoid coil 89 is energized by the closing of switch 91, armature 88 is displaced to the left by magnetic attraction to move plunger 81 to the left to its second or venting position, shown in FIG. 2, in which working chambers 24a and 63a are connected with sump 44 via branch line portions 75b and 75c, respectively, common portion 75a, port 74, groove 86, port 77, and conduit 79.

OPERATION

The operation of the hydraulic starting system may now be described.

(1) Motoring Operation

Assuming that the hydraulic unit 3 is at rest and that valve 42 is in its second position, the fluid path from accumulator 40 to high pressure port 8 is closed and the initial pressures in port 8 and control valve inlet chamber 47 are zero. Plunger 55 is maintained in its FIG. 2 position by spring 64 so that working chamber 31a of positioning motor 31 is vented to sump via conduit 51, passage 49, groove 59, passage 52 and conduit 53. Assuming also that switch 91 is closed to energize solenoid 89, plunger 81 is maintained in its FIG. 2 position against the bias of spring 87 to connect working chambers 24a and 63a with sump 44, as shown. Since working chamber 24a is vented, spring seat sleeve 22 engages the housing internal wall surface 4a and spring 23 biases sleeve 19 to the left relatively to sleeve 22 to position cam plate 15 in its maximum stroke-establishing pumping position, as shown by the broken lines in FIG. 2. Owing to the venting of working chamber 63a, seat 63 is in its FIG. 2 position to establish the first "reference pressure" value against which the pressure in inlet passage 47 is compared.

For the purpose of the following discussion, it will be assumed that the first "reference pressure" established by spring 64 is 1500 p.s.i., that the accumulator 40 is under an initial pressure of 3000 p.s.i., and that pressures of 300 and 500 p.s.i., respectively, in working chamber 31a are required to hold cam plate 15 in the neutral position of FIG. 2 and the maximum motoring position

of FIG. 1 against the bias of spring 23 when chamber 24a is vented.

When inlet valve 42 is opened, pressure fluid is transmitted to port 8, through conduit 41 and to inlet passage 47 of control valve 46 via conduit 48. The fluid in passage 47 acts on the right-hand end surfaces of lands 57 and 58 and shifts plunger 55 to the left against the bias of spring 64. As the pressure rises to the reference value of 1500 p.s.i., plunger 55 moves to a lap position in which land 57 interrupts communication between motor passage 49 and exhaust passage 52. A further rise in pressure in inlet passage 47 causes plunger 55 to move further to the left to interconnect inlet passage 47 with motor passage 49 through slots 62 and groove 61. Pressure fluid is now transmitted to working chamber 31a through conduit 51. The pressure in working chamber 31a rises rapidly to system pressure, and since at this time this pressure is greater than the 500 p.s.i. required to hold cam plate 15 in the maximum motoring position of FIG. 1, the motor 31 immediately moves the cam plate 15 to that position. The cam plate 15 remains in this position as long as system pressure is above 1500 p.s.i.

The fluid supplied to high pressure port 8 from the accumulator 40 is fed through internal housing passages (not shown) and through the passages of valve plate 7 to the longitudinal bores 11 of the rotary cylinder barrel 6 to displace pistons 12 to the left against cam plate 15. The pistons react with the inclined cam plate to apply maximum initial torque on drive shaft 5 with the result that internal combustion engine 37 is driven in the starting direction by the hydraulic unit 3 through the splined coupling 36 and the mechanical connection 38.

As the speed of rotation of the hydraulic motor 3 increases, it imposes an increasing demand on the accumulator 40 and consequently the supply pressure decreases progressively. For the purpose of the following discussion, it is assumed that by the time the accumulator pressure has decreased to 1490 p.s.i., the internal combustion engine has accelerated to starter cut-out speed. As the hydraulic unit 3 accelerates to approximately 93% of starter cut-out speed, the accumulator pressure decreases from 3000 to 1600 p.s.i. and a similar pressure reduction occurs in working chamber 31a. Throughout this period of time, the pressure in working chamber 31a is sufficient to maintain cam plate 15 in its maximum stroke-establishing motoring position against the bias of spring 23. Consequently the hydraulic motor continuously applies to the internal combustion engine 37 the maximum possible torque obtainable from the fluid pressure source. During the final period of acceleration of the hydraulic unit, i.e., as the speed of the internal combustion engine increases from 93% to 100% of starter cut-out speed, the accumulator pressure drops below the "reference pressure" of 1500 p.s.i. thus permitting spring 64 to move plunger 55 to the right from the lap position and again vent working chamber 31a. As the pressure in working chamber 31a decreases below 500 p.s.i., spring 23 commences to move cam plate 15 toward the neutral position, and, when it reaches 300 p.s.i., the cam plate will be in that position.

As the pressure in working chamber 31a approaches 300 p.s.i., the internal combustion engine approaches starter cut-out speed, and, when the working chamber pressure is 300 p.s.i., the engine will have achieved independent operation and will be driving hydraulic unit 3 as a pump. Because of this, the pressure in conduit 48, and in inlet passage 47, is immediately restored to 1500 p.s.i. and the plunger 55 of control valve 46 is returned to the lap position thereby interrupting the vent path from working chamber 31a. Since there is no demand for hydraulic fluid at this time, system pressure will remain at 1500 p.s.i. and control valve 46 will maintain cam plate 15 in neutral position. However, should system pressure decrease as a result of leakage, spring 64 will shift plunger 55 to the right from the lap position

to thereby vent working chamber 31a and permit spring 23 to move cam plate 15 away from neutral position a small distance in the direction of maximum pumping position. This action causes the pump to supply fluid to the system and when the pressure is restored to 1500 p.s.i. and the rate of discharge from the pump equals the rate of leakage, plunger 55 will be shifted back to the lap position. It should be realized that the cam plate position established by system leakage is very close to the neutral position and that for all practical purposes, the hydraulic unit is now imposing a minimum torque on the internal combustion engine. This is a desirable feature because it permits the engine to accelerate rapidly.

15

(2) Pumping Operation

After the internal combustion engine has accelerated to a speed at which it develops sufficient power to drive the hydraulic unit under load, switch 91 is opened to initiate the high pressure pumping operation. Opening of switch 91 de-energizes the holding solenoid 89 and allows spring 87 to move valve plunger 81 to the right to connect working chambers 24a and 63a with high pressure port 8 via branch conduits 75b and 75c, respectively, common conduit 75a, port 74, groove 85, port 72, conduit 73 and conduit portion 48a. The pressure fluid in working chamber 24a moves piston 26, piston rod 27, and sleeve 22 to the left to increase the biasing force applied to cam plate 15 by spring 23. It is assumed that with sleeve 22 in its left-hand position, a pressure of 150 p.s.i. is required in chamber 31a to initiate movement of cam plate 15 in the counterclockwise direction against the bias of spring 23, and that a pressure of 350 p.s.i. is required to position the cam plate in its neutral position. Sleeve 22 now constitutes a stationary cam stop preventing movement of the cam plate from its neutral position toward its maximum stroke-establishing motoring position.

The pressure fluid in working chamber 63a moves spring seat 63 to the right into engagement with stop 69 with the result that the compression load in spring 64 is increased to establish a second "reference pressure" value (for example, 3000 p.s.i.). Plunger 55 is now in its FIG. 2 position, venting chamber 31a.

With cam plate 15 in its maximum stroke-establishing pumping position, the hydraulic unit is driven by the internal combustion engine and supplies fluid from high pressure port 8 to the accumulator 40 via conduit 41. After the accumulator has been recharged to its initial pressure of 3000 p.s.i., which is the second "reference pressure," plunger 55 is shifted to the left to its lap position. When the pressure exceeds 3000 p.s.i., plunger 55 is shifted further to the left to admit fluid to chamber 31a via slots 62, groove 61, chamber 49 and conduit 51. As the pressure in chamber 31a increases from 150 p.s.i. to 350 p.s.i., cam plate 15 is progressively pivoted from its maximum stroke-establishing position to its neutral position. Due to the provision of the cam stop (i.e., sleeve 22 in its left-hand position), movement of the cam plate in the counterclockwise direction beyond the neutral position is prevented. Since the cam plate is now in its neutral position, the hydraulic unit is in an idling, minimum-displacement condition. In the event that the pressure in conduit 48 drops below 3000 p.s.i. (as a result of internal leakage, for example), plunger 55 is shifted to the right by spring 64 to vent chamber 31a, and when the pressure in this chamber drops below 350 p.s.i., cam plate 15 is displaced in the clockwise direction by spring 23 to effect an increase in displacement of the pump to compensate for the leakage. When the pressure in conduit 48 is returned to 3000 p.s.i., plunger 55 is moved to the left to the lap position to trap the fluid in chamber 31a, whereby cam plate 15 is maintained in its leakage compensating position.

75

Inlet valve 42 may now be shifted to its second position

in which accumulator 40 is isolated and high pressure port 6 is connected with the vehicle hydraulic system via conduits 41b and 43. As a result of system demand, the pressure in conduit 43 and passage 47 decreases below 3000 p.s.i. and plunger 55 is shifted to the right to vent working chamber 31a. As the pressure in chamber 31a decreases from 350 to 150 p.s.i., cam plate 15 is pivoted in the clockwise direction toward its maximum stroke-establishing pumping position by spring 23. When the system demand is met by the pump, the pressure in conduit 43 rises to the second "reference pressure" value and plunger 55 is shifted to the left to its lap position to discontinue venting of chamber 31a. The position of the cam plate 15 now establishes a rate of discharge equal to the rate of demand for hydraulic fluid.

Should the system demand decrease and the pressure rise above 3000 p.s.i., plunger 55 is shifted further to the left to supply fluid to chamber 31a, and thus cause motor 31 to effect a progressive decrease in cam angle. When the cam reaches that position in which the rate of discharge from the hydraulic unit 3 matches the new demand and system pressure is restored to 3000 p.s.i., plunger 55 moves back to its lap position and again interrupts flow to working chamber 31a. Thus it is apparent that during pumping operation, the hydraulic unit operates as a pressure-compensated pump, the displacement of which is automatically varied by valve 46 to maintain substantially constant the selected maximum system pressure.

As stated previously, the drawings and description relate only to the preferred embodiment of the invention. Since many changes can be made in the structure of this embodiment without departing from the inventive concept, the following claims should provide the sole measure of the scope of the invention.

What is claimed is:

1. In combination

- (a) hydraulic motor-pump unit having high and low pressure ports and a displacement control element movable between first and second maximum displacement-establishing positions on opposite sides of a zero displacement-establishing position for varying the displacement of and changing the direction of flow through the unit;
- (b) a source of pressure fluid, having a decaying pressure characteristic, for driving the unit as a motor;
- (c) a conduit connecting the source with the high pressure port;
- (d) a reservoir connected with the low pressure port;
- (e) spring means connected with the displacement control element and biasing it toward the second maximum displacement-establishing position;
- (f) control means connected with the displacement control element and responsive to the pressure at the high pressure port for moving said element toward the first maximum displacement-establishing position as the pressure rises above a predetermined value;
- (g) stop means associated with the displacement control element and shiftable between effective and ineffective positions in which, respectively, it prevents and permits said element from moving from the zero displacement-establishing position toward the first maximum displacement-establishing position;
- (h) selecting means for shifting the stop means between its effective and ineffective positions.

2. The combination defined in claim 1

- (a) in which the spring means includes a spring seat shiftable between high spring-load and low spring-load positions; and
- (b) in which the seat and the stop means are interconnected, whereby the seat is shifted to the high spring-load and low spring-load positions, respectively, as the stop means is shifted to the effective and ineffective positions.

3. The combination defined in claim 2

(a) in which the control means comprises

- (1) a fluid pressure positioning motor connected with the displacement control element and arranged to move that element toward the first maximum displacement-establishing position,
  - (2) a control valve connected with the positioning motor, the high pressure port and the reservoir and including a movable member shiftable between a first position in which the positioning motor is connected with the reservoir and a second position in which the positioning motor is connected with the high pressure port, the movable member having an intermediate lap position in which the positioning motor is isolated from both the reservoir and the high pressure port,
  - (3) means biasing the valve member toward the first position,
  - (4) means responsive to the pressure at the high pressure port for shifting the valve member toward the second position, and
  - (5) means for varying the bias exerted by the biasing means between high and low values; and
- (b) in which the selecting means includes means for operating the bias varying means simultaneously with shifting of the stop means and the spring seat, whereby the bias exerted by the biasing means is said low value when the stop means is in the ineffective position and the spring seat is in the low spring-load position, and the bias exerted by the biasing means is said high value when stop means and the spring seat are in their other positions.

4. In combination

- (a) a hydraulic motor-pump unit having high and low pressure ports and a displacement control element movable between first and second maximum displacement-establishing positions on opposite sides of a zero displacement-establishing position for varying the displacement of and changing the direction of flow through the unit;
- (b) a source of pressure fluid, having a decaying pressure characteristic, for driving the unit as a motor;
- (c) a conduit connecting the source with the high pressure port;
- (d) a reservoir connected with the low pressure port;
- (e) spring means connected with the displacement control element and biasing it toward the second maximum displacement-establishing position;
- (f) said spring means including a spring seat shiftable between high spring-load and low spring-load positions;
- (g) a fluid pressure shifting motor connected with the spring seat and arranged to shift the spring seat toward the high spring-load position;
- (h) selecting means for connecting the shifting motor with the high pressure port and the reservoir, respectively; and
- (i) control means connected with the displacement control element and responsive to the pressure at the high pressure port for moving said element toward the first maximum displacement-establishing position as the pressure rises above a predetermined value.

5. The combination defined in claim 4

(a) in which the control means comprises

- (1) a fluid pressure control motor connected with the displacement control element and arranged to move that element toward the first maximum displacement-establishing position,
- (2) a control valve responsive to the pressure at the high pressure port for connecting the control motor with the high pressure port and the reservoir, respectively, as the pressure rises above and decreases below said predetermined value, and

- (3) fluid pressure motor means associated with the control valve and effective when pressurized to establish a high limit for said predetermined value, and when vented to establish a low limit for said predetermined value; and
- (b) in which the selecting means is connected with the fluid pressure motor means, whereby the shifting

motor and the fluid pressure motor means are simultaneously connected with the high pressure port and the reservoir, respectively.
